UNITED STATES PATENT OFFICE.

FRIEDRICH VEITH, OF GELNHAUSEN, GERMANY.

PUMP FOR PNEUMATIC TIRES.

SPECIFICATION forming part of Letters Patent No. 504,853, dated September 12, 1893.

Application filed April 3, 1893, Serial No. 468,846. (No model.) Patented in Germany September 24, 1892, No. 9,856; in England November 21, 1892, No. 21,120, and in France December 19, 1892.

To all whom it may concern:

Be it known that I, FRIEDRICH VEITH, a subject of the King of Prussia, residing at Gelnhausen, Prussia, German Empire, have 5 invented a new and useful Improvement in Pumps, (for which I have obtained Letters Patent in Germany, September 24, 1892, No. 9,856; in England, provisional Patent No. 21,120, November 21, 1892, and in France 10 December 19, 1892, which has not yet been numbered,) of which the following is a full, clear, and exact description, reference being had to the accompanying drawings, in which—

15 Figure 1 is a central vertical section of my improved device, the piston being shown in full lines, with parts broken away. Fig. 2 is an enlarged sectional detail clearly showing the plunger head and mechanism connected therewith.

20 My invention relates to the construction of a device more particularly adapted to be used on cycles, and like vehicles, wherein pneumatic tires are used, and said invention consists, mainly, in constructing an air pump 25 with a hollow plunger rod for containing the cementing, or other liquid, and with means for expelling said liquid.

Said invention consists also in the novel 30 arrangement and combination of the parts hereinafter described and claimed. It frequently occurs that vehicles provided with pneumatic tires are disabled and rendered unfit for use by the tires being punctured, 35 allowing them to collapse.

The object of my invention is to produce an efficient and reliable means for repairing the punctured tire, and inflating the same when required.

40 In the drawings *b* represents the cylinder of an air pump of any suitable construction, which is provided with a cap *m*, and a screw-threaded nozzle *h*, adapted to be closed by a screw-threaded plug *f*. Within this cylinder 45 *b* is adapted to operate a hollow piston rod *a*, the central chamber of which forms a chamber *a'* for the reception of a cementing or other liquid, there being sufficient space between said piston and the walls of the cap *m* 50 to allow of the admission of air within the cylinder *b*, back of the piston head.

i designates a flexible packing which is connected to the head of the piston preferably by a hollow screw *k*, as shown in Fig. 2. Within this hollow screw *k* is adapted to fit 55 with the open end outward a second hollow screw, or screw bolt, *d*, provided with openings *x* and nut *c*.

g is a packing which is interposed between the head of the bolt *d* and the end of the 60 screw *k* for preventing the liquid from escaping from the chamber *a'* in the piston rod when the nut *c* is tightened. To the end of this piston rod that extends beyond the end of the cylinder *b* is attached a suitable handle *l* so arranged as not to interfere with the opening *l'* communicating with chamber *a*, said opening being shown in Fig. 1, provided with a removable nozzle *e*. It is here explained that the removable nozzle *e* and the 65 plug *f* can be interchangeably used in the nozzle *h* of the pump cylinder, or in the opening *l'* in the piston rod, for purposes which 70 will be hereinafter described.

When it is desired to put my device into 75 use, say, for example, for cementing the puncture in the tire, it is necessary to loosen the nut *c* on the bolt *d* sufficiently to allow air to enter the liquid chamber *a'*; the plug *f* is then fastened in the nozzle *h* to prevent the 80 escape of air, and the removable nozzle *e* is fastened in the opening *l'*. The cylinder is then forced toward the nozzle *e* in the piston rod, while the latter is held stationary by the handle *l*. The compression of air between 85 the nozzle end of the cylinder and the piston and causes air to enter through the hollow bolt *d* to the liquid contained in the chamber *a'* forcing the same, or as much thereof as is required, through the nozzle *e*.

90 After the puncture has been mended, and it is desired to inflate the tire, it is necessary to tighten up nut *c* to prevent the liquid from escaping through the bolt *d*; fasten the plug *f* in the opening *l'* and the nozzle *e* may, 95 if desired, be fastened in the cylinder nozzle *h* when the device can be used as an air pump. It is obvious that there are many changes in detail that I might make, without departing from the spirit of my invention, 100 the main object being to provide a piston rod with a liquid containing chamber, and

having means for withdrawing said liquid. It is also obvious, that while I have described my device as adapted for use in connection with cycles, and like vehicles, having pneumatic tires, it may be used for other purposes.

Having described my invention, what I claim, and desire to secure by Letters Patent, is—

- 10 1. In a pump of the character described, the combination with an outer cylinder of a piston operating in said cylinder, the rod of said piston having a liquid containing chamber therein, and means, substantially as described for forcing the liquid therefrom, substantially as and for the purposes herein set forth.
- 15 2. In a pump of the character described, the combination with an outer chamber of a piston operating therein, the rod of said piston having a liquid containing chamber in open communication with the exterior of the pump, means for closing said communication, and means substantially as described, for forcing
- 20 3. In a pump of the character described, the combination with an outer chamber of a piston operating therein, the rod of said piston having a liquid containing chamber in open communication with the exterior of the pump, and an adjustable hollow perforated bolt in
- 25 4. In a pump of the character described, the combination with an outer chamber of a piston operating therein, the rod of said piston having a liquid containing chamber in open communication with the exterior of the pump, and an adjustable hollow perforated bolt in

piston operating therein, the rod of said piston having a liquid containing chamber in communication with the exterior of the pump, and an adjustable hollow perforated bolt in said piston, as and for the purposes specified.

4. The combination of the hollow screw *k*, hollow perforated bolt *d* within the screw *k*, and nut *c*, all arranged substantially as and for the purposes specified.

5. In a pump of the character described, the employment of a hollow piston-rod which is adapted to form a reservoir for a liquid, and which has a valve at its piston end, which valve when used as an air pump is closed, and when used as a liquid ejector is opened, said piston rod having at its outer end a nozzle opening, which is adapted to be closed, and having also a handle.

6. An air pump having air ejecting aperture at one end, and a hollow piston rod having an opening at the other end, to be used when the other is closed, substantially as and for the purposes specified.

FRIEDRICH VEITH.
